DELAY TIMER

Paul R. Pittman, Jr., Dayton, Ohio, assignor to Globe Industries, Inc., Dayton, Ohio, a corporation of Ohio
Filed Apr. 19, 1962, Ser. No. 188,788
5 Claims. (Cl. 200—33)

This invention pertains to a timing device or an instrument for emitting an electrical pulse at a preselected interval after actuation.

There are many applications where a timing device of the character described is applicable, such as for the operation of bomb release equipment in aircraft.

One object of the invention is to provide a time delay switch which is of light weight and small dimension, and thus suitable for mounting on the instrument panel of an aircraft. A further object is to provide a time delay switch which is extremely accurate in repeatedly operating its actuating mechanism at the exact interval preselected. A still further object of the invention is to provide in a time delay switch employing a miniature motor, a simple but exact timing means for insuring constant output speed of such motor.

These and other objects of the invention will become more readily apparent upon a reading of the description following hereinafter and upon reference to the drawings, in which:

FIGURE 1 is an exploded perspective view of the time delay switch of the invention,

FIGURE 2 is a cross-sectional view through the assembled time delay switch of the invention,

FIGURES 3 and 4 are cross-sectional views taken along respective lines 3—3 and 4—4 of FIGURE 2, and

FIGURE 5 is a schematic line diagram illustrating the operative circuitry of the invention.

In the time delay switch of the invention an interval selection dial 62 is manipulated to select a time interval or switch position.

Briefly stated, the device operates as follows: When power is turned on, the motor 40 rotates and drives an escapement 18. The escapement 18 controls the output speed or rotational speed of the motor output shaft 42. When power is applied to a clutch 120—132, this output shaft 42 is then coupled to a cam shaft 103 and the timing sequence commences. After the cam shaft has been rotated for the selected timing interval, it will be positioned so as to actuate switch actuating members and switches, which will accomplish the purpose of providing an output signal and shutting off the motor.

As indicated in FIGURE 1, the time delay switch 1 of the invention comprises a housing or cover 2 in the form of a can, and a second end housing 4, for the terminal board mounting which is assembled to the housing 2 by screw fasteners 5 to enclose the unit. The remaining enclosure is formed by the mounting plate 6 to which the cover 2 is sealed. Affixed to the mounting frame or plate 6 as by the screw fastenings 8 is the main frame 10. Affixed to the main frame 10 as by screw fastening 12 is the mounting plate 14, which has attached thereto as by the fastening 16 an escapement mechanism 13. Such escapement mechanism is not disclosed in detail herein since it is deemed to be well-known in the art. Escapements which may be used can be of the Junghans type.

Also affixed to the mounting plate 14 by a series of spacer sleeves such as 22, and the long screw or bolt 24, is a mounting plate 28. This mounting plate 28 serves as a means for positioning the various components, and also provides a means for mounting the terminal board 30 as by the fasteners 32 and 34, thereto.

A motor 40 having an output shaft 42, which is splined

2

at its end as at 44, is mounted through the mounting plate 14 and affixed to a hub 46 on such mounting plate.

The main frame 10 has a forwardly extending hub 59 which forms a housing for a pair of bearing means 52 and 54. These bearing means journal the main shaft 56. The shaft 56 has fixedly mounted at one end a detent plate 58, and is provided at the other end with a flattened reduced portion 60. A dial 62 is mounted on the flattened portion 60 of the shaft 56 by means of a set screw 64 which passes through the dial 62 and through a hub 66, to bear against the flattened portion 60.

Mounted on the inner surface of the main frame 10 is a switch 70 which is insulated from the frame by an insulator 72. The switch 70 serves to actuate a relay 74 which is mounted to the mounting plate 28. The means for actuating this switch 70 includes a detent lever 75 which is affixed to a mounting block 76 and which is urged towards the actuating button of the switch 70 by a detent spring 78. The spring 78 is also mounted to the mounting block 76. The mounting block, in turn, is affixed to the front wall of the main frame 10. The detent spring has formed centrally thereof a series of teeth 80 which cooperate with a series of teeth 82 on the detent plate 58. The teeth 80 ride between the teeth of the plate 58, and when the shaft 56 is rotated, the detent lever 75 is raised to actuate the switch 70; an actuating screw or knob 84 being employed for that purpose, which cooperates with the switch button 86.

The detent plate 58 is also provided with the stop pin 90 (see also FIGURE 3) which cooperates with the mounting block 76 to provide a positive mechanical stop for the rotational positioning of the dial 62.

Mounted on the outer side of the detent plate 58 are a pair of switches 92 and 94 (see FIGURES 1 and 4). These switches serve to produce an output signal and cut off power to the motor, respectively, when the driving sequence has been completed. FIGURE 4 illustrates the relationship of the switches with respect to the cam shaft 103. The switches 92 and 94 are insulated from the detent plate 58 by insulating pads such as 98. Fastening means 102 are provided for mounting these switches to the plate. An actuator 104 is provided with a pivotal mounting hinge 106 to cooperate with the mounting bracket 107. The end 109 of the actuator 104 is positioned to contact the cam shaft 103, so that actuator 104 can actuate the switch button 110 on the switch 92. The switch 94 is so mounted that its actuating button 112 is directly actuated by the cam shaft 103.

The clutching mechanism comprises an electromagnetic core 120 which has mounted thereon the solenoid coil 122. A solenoid sleeve 124 is fitted within the solenoid coil 122 and the solenoid plunger 126 is caused to reciprocate upon transmission of power to coil 122. A housing 130, together with the end plate 132 serves to complete the clutch unit. Upon actuation of the clutch the solenoid plunger 126 is pulled to the left as viewed in FIGURE 2. The solenoid plunger 126 has threaded fastened to it an actuating rod 134 which is also threaded at its outer end as at 136. The threaded portion 136 serves, by means of the fastenings 138 and 140, to capture an actuating plate 142. The other end of the actuating plate is yieldably mounted on a stud 150, being urged to the right, as viewed in FIGURE 2, by the spring 152. A nut 154 serves to adjustably and fixedly position the stud 150 within the threaded hole 156. Thus, the mounting of the end of plate 142 on the stud 150 serves as a pivotal mounting to permit the actuating plate 142 to move to the left, as viewed in FIGURE 2, and thereby cause engagement of the clutching mechanism as described hereinafter.

The escapement drive shaft 160 has a spur gear 162

mounted thereon which mates with the appropriate gearing 164 within the escapement 18. As indicated in FIGURE 2, the drive shaft 160 is mounted through a bearing 170 in the mounting plate 172. The actuating lever 142 is provided with an opening 143 to permit the mounting thereof about the cam shaft 198. The cam shaft 198 is a hollow shaft which is rotatably mounted upon the drive shaft 160. The end of the drive shaft 160 is reduced into a tenon portion 163 which pilots within the shaft 56.

A bearing 180 and a washer 182 are mounted on the left side of the actuating lever 142, so that when the lower end of the actuating lever 142 is drawn to the left, as viewed in FIGURE 2, the bearing 180 and the washer 182 are brought into engagement with a shoulder 193 on the cam shaft 198 which is integral with the clutch plate 192. The clutch plate 192 may be provided with a clutch facing 194, and the spur gear may be provided with a clutch facing 195, if desired (see FIGURE 2). Upon actuating the solenoid the clutch face 194 engages the clutch facing 195. Since the spur gear 196 is being driven by the motor 40, the cam shaft 198 will commence rotation. Rotation of the cam shaft 198 will cause the winding up of the spring 190. The spring 190 is affixed at its inner end to the shoulder 193 on the cam shaft 198 and is anchored at its outer end on a stud (not shown) mounted on the frame 10. When the cam shaft has been driven so as to actuate the switches, and thereafter power is cut off to the solenoid, the clutch is released and the torsion spring 190 returns the clutch plate 192 to its home position. This home position is arrived at by a lug 196 protruding from the clutch plate 192 which hits up against a stop screw 198 affixed to a block 200 on the mounting plate 14.

The spline 44 of the motor shaft 42 meshes with the spur gear 196 which is in turn affixed to the escapement drive shaft 160, so that the gear 162 both drives the escapement, and is controlled in its rotation by the escapement.

It is thus seen that in the time delay switch of the invention, a motor is combined with an escapement wherein the motor and escapement are geared to a common drive shaft which, in turn, is clutched to a cam shaft to actuate switches. With reference now to the schematic wiring diagram of FIGURE 5, it is seen that when the external start switch 300 is closed, plus power is transmitted through line 302, the relay contacts 304, 306, switch 94 and line 305 to the motor 40. At the same time, power flows from relay switch contact 304, through line 308 to the clutch coil 122, to permit transfer of power by clutch actuation to the cam shaft. When the cam shaft 198 has been rotated for the preset time delay, the switch 94 is operated to open position, and the switch 92 is operated to closed position. When switch 92 is engaged, a signal will appear at the output terminal 310 since the power flowing through line 302 and switch contacts 304, 306 will pass through the switch 92 to the output terminal 310. At the same time that this occurs, the motor 40 will be stopped, since no power will be transmitted through line 305 to the motor. However, power still flows through line 308 so that the clutch remains engaged and the torsion spring remains wound up. To reset the mechanism, the start switch 300 is opened to remove power from line 308 and the clutch coil 122, so that the unit is re-zeroed.

In the event the control or time interval selector knob 62 is accidentally moved during the timing cycle, the switch 70 is momentarily actuated from its position engaging its contact 312 to the position engaging the contact 314. When the contact 314 is engaged, the plus power in line 302 will be transmitted to the relay coil 316 to actuate the relay and pull down the switch arm 304 from its position in contact with the contact 306, to one where it contacts the contact 318. The relay switch 74 will remain in this position regardless of whether switch 70 returns to its normally open position or stays closed. With the contact switch arm 304 engaging the

5 contact 318, power will be removed from both the clutch coil 122, i.e., line 308, and the motor 40, i.e., line 305. In order thereafter to reactivate the unit, the start switch 300 must be reopened so that it can deactivate the relay 74. The resistor 320 is an arc suppression resistor and the network 322 is employed to provide damping to the motor, so that when power is removed the motor will immediately be stopped.

6 The delay timer of the invention operates as follows: The timing interval desired is first set by rotating the knob 62 which in turn rotates shaft 56 and positions the detent plate 58. Positioning of the detent plate changes the relative position of switches 92 and 94 with respect to their switch actuators. The setting of switch 92 determines the time interval between power-on until signal output; and the setting of switch 94 determines the time of power cut-off to the motor (which as indicated in FIG. 4 will always be immediately following the signal output).

7 When the switch 300 is operated to turn power on, both the motor 40 and the coil 122 are actuated. When coil 122 is actuated it moves the plunger 126 to the left as viewed in FIG. 2; and thus also moves the actuating rod 134 and actuating plate 142 to the left as viewed in FIG. 2. Operation of the actuating plate causes engagement of the clutch by moving the bearing 180 and washer 182 into engagement with the surface 193 on the clutch plate 192. This causes the bringing together of the clutch faces 194 on the shaft 198 and 195 on the gear 196; thus commencing rotation of the cam shaft 198. Actuation of the motor causes rotation of the motor shaft 42 and consequent rotation of the spur gear 196, with which the splined portion 44 of shaft 42 is in mesh. However, since the gear 196 is also affixed to the escapement drive shaft 160, the gear 162 both drives the escapement and also is itself controlled in its rotation by the escapement. The escapement therefor acts as a speed limiter for the motor drive; and by this unique "closed mechanical loop" action insures extremely accurate timing intervals. Rotation of the cam shaft 198 for a sufficient interval will cause actuation of the switches 92 and 94 as above indicated.

8 Although a specific embodiment of the invention has been shown and described, it is readily understood that various modifications and rearrangement of the parts may be made without departing from the spirit and scope of the invention as defined in the appended claims.

9 What I claim is:

10 1. Time delay means comprising, in combination: an electric motor having an output shaft provided with a first drive means; an escapement drive shaft, a second drive means affixed to rotate with said drive shaft, said first and second drive means being in engagement with one another; an escapement means driven by said second drive means whereby the drive shaft is permitted to rotate only at a precise constant speed; an electric switch; switch actuating means for operating said switch at the end of a preselected timing interval; and electromagnetic means for selectively coupling said drive shaft to said switch actuating means for operating same when said motor is activated.

11 2. The time delay means of claim 1 wherein said selective coupling means comprises an electromagnetic clutch means and said switch actuating means includes a cam shaft; said switch being so mounted as to be positionable at various relative timing positions with respect to said cam shaft; said cam shaft being rotated upon energization of the clutch means to operate said switch.

12 3. The time delay means of claim 1 including a second switch; an electrical circuit including said motor, first and second switches and said electromagnetic means, said first switch being so interconnected as to disrupt power flow to said motor, and said second switch being so interconnected as to provide a power output signal.

4. The time delay means of claim 3 wherein said switches are so constructed and arranged that the switch actuating means first operates said first switch and thereafter said second switch.

5. The time delay means of claim 1 including means comprising a relay switch for disabling the power supply to said motor automatically in the event the preselected timing interval is changed after initial activation of said motor.
